CONDUIT BENDER

Lawrence M. Curtiss, Mountainside, N.J., assignor to The Thomas & Betts Co., Elizabeth, N.J., a corporation of New Jersey

Filed Feb. 20, 1959, Ser. No. 54,689

Term of patent 14 years

(Cl. D54—13)

Fig. 1

Fig. 2

Fig. 3

Fig. 4

Fig. 1 is a top plan view of a conduit bender showing my new design;

Fig. 2 is a side view in elevation;

Fig. 3 is a bottom plan view of the same; and

Fig. 4 is a view in elevation of the opposite side of the conduit shown in Fig. 2.

I claim:

The ornamental design for a conduit bender, as shown.
